UNITED STATES PATENT OFFICE.

GARRET B. OSTERHOUT, OF PROVIDENCE, RHODE ISLAND, ASSIGNOR TO WILLCOX & GIBBS SEWING MACHINE CO., OF NEW YORK, N. Y., A CORPORATION OF NEW YORK.

SEWING-MACHINE TAKE-UP.

1,253,518.

Specification of Letters Patent. Patented Jan. 15, 1918.

Application filed October 23, 1916. Serial No. 127,180.

To all whom it may concern:

Be it known that I, GARRET B. OSTERHOUT, a citizen of the United States of America, and a resident of Providence, Rhode Island, have invented a new and useful Improvement in Sewing-Machine Take-Ups, which invention is fully set forth in the following specification.

This invention relates to a sewing machine take-up or take-up means, and to such means designed especially to take up the looper threads in the machine known commercially as the Willcox & Gibbs Sewing Machine Company's "Flatlock machine," shown for example in the patent to A. A. Merritt, No. 1,041,652, dated October 15, 1912.

The invention consists of an arrangement of take-up parts in the work-arm of the machine in a position relatively near to the stitch-forming parts where the slackening of the looper threads occurs. Thus the action of taking-up the said slack when the loopers start to enter needle thread loops is not impeded by the friction of pulling the threads through intermediate guides as is the case when the take-up means are located relatively distant from the stitch-forming parts, particularly the loopers. Hence, the take-up action is more direct, the looper threads are under better control and are more responsive to variations of the tension imposed by tension devices. These and other advantages will be more fully understood from the detailed description and drawings.

What is now believed to be the preferred embodiment of the invention is illustrated in the accompanying drawings, wherein—

40 Figure 1 is a plan view of a sewing machine embodying the invention;

Fig. 2 is an elevation with parts in section on line 2—2 of Fig. 1;

Fig. 3 is a longitudinal section through the free end of the work-arm with the parts inside of the arm shown in elevation;

Figs. 4 and 5 are plan views showing the looper mechanism and the associated looper-

thread take-up means in different positions, respectively;

Fig. 6 is a transverse section on the line 6—6 of Fig. 3;

Fig. 7 is a transverse section on the line 7—7 of Fig. 1;

Fig. 8 is a detailed perspective view of the looper-thread take-up parts;

Fig. 9 is a schematic view showing the path of the looper-threads through the parts of the machine; and

Fig. 10 comprises four diagrammatic views illustrative of the action of the looper-threads at different stages of the elliptical movement of the loopers.

The frame and work-arm of the machine, including the two hollow standards 40, 41, Fig. 1, the hollow connecting bridge 42 of the frame,—the work-arm including the horizontal part 50, vertically depending part 51, and the horizontal work-supporting part and free end of the arm 53, with its removable cover 54,—the thread guide-plate 682,—thread tension-plates 684,—bracket 678 on which said guide and tension-plates are mounted,—the set of four thread-guiding hooks 685,—the presser-foot (part of which shows in Fig. 1),—the needles (Fig. 3),—the looper-lever or bar 375,—the means (part of which is shown at 410, Fig. 3) for imparting movement in a circular path, see dotted circles a' , Figs. 4, 5, to one end of the looper-lever,—the guide-plate 412 and bridge piece 912 (Fig. 3) between which the looper-lever works,—the rotatable fulcrum block 413 in which the looper-lever moves longitudinally and which turns with the lever in the compound movement thereof causing the points of the loopers to travel in elliptical paths such as shown by dotted lines b , Figs. 4 and 5,—block 418 (Fig. 7) held in place by screws 419, 420,—fulcrum pin 334 (Fig. 7) for the two feed levers (not shown) which carry the fulling feed-member 340 and the stitch-feed member 359 (Fig. 3), respectively,—the thread groove or channel 298 (Figs. 4, 5 and 7) in the front wall of the part 53 of the work-arm,

the threads passing over a rounded edge 53^a in leaving said channel—are all similar in construction and functioning to the similarly designated parts in said Merritt Patent No. 1,041,652.

The trough-like threadway, with its inclined portion 705, vertical portion 706, vertically movable slide 711 having four longitudinal thread grooves and blocks 714 with 10 thread eyes 713 (Fig. 3), and cover 723, are substantially the same in construction and functioning as the correspondingly designated parts in Figs. 66-73 of said Merritt patent, except that the thread trough has only 15 an inclined portion 705 and a vertical portion 706 with one bend for the thread where said portions join, and the cover 723 extends along the inclined portion, whereas in the patent there is an additional horizontal portion 20 with another bend where it joins the inclined portion and the cover is on the horizontal portion.

The looper carrier 16 pivotally mounted on the end of the looper-lever by a pivot-screw 26,—the four loopers 17, and the plate 27 with four thread eyes for the looper-threads,—the loop-spreader 29 having a tail-piece 33 pivoted on a screw-pivot 32 and supported by a bracket arm 36,—the roller 37 on 30 tail-piece 33 engaging a cam groove of part 38 on the looper-lever,—and the throat plate or work-plate 11 through which the needles and the feed-members operate—are all similar in construction and functioning to the 35 corresponding parts shown in patent to G. B. Osterhout, No. 1,134,483, dated April 6, 1915.

77 is a stationary take-up member fitting and adjustable in a longitudinal depression 40 or groove in the inner face of the wall of the free end or part 53 of the work-arm. A screw 78 in a countersunk slot in the front wall of the work-arm (Figs. 4 and 5) secures member 77 in its desired position of adjustment, said adjustment determining the degree of take-up action. Two fingers 79, 79 projecting from the outer end of member 77 form an intervening notch in which the looper threads engage. 71 is a movable take-up member secured to the looper-lever 375 by screws 72, 72. A vertical portion of said member has a spring 73 secured thereto by a screw 74 (Fig. 8), the upper end of said spring resting in a notch 76 between two 55 fingers or lugs projecting horizontally from part 71. A slight clearance, say of about one thirty-second of an inch, around the upper end of spring 73, which spring does not contact the wall of notch 76, provides a 60 space through which the looper threads may be entered beneath the spring to the space covered thereby, from which space the threads can not escape during movement of the parts.

As shown in the schematic view (Fig. 9), 65 the path of the looper-threads *a* is from guide 682, between tension plates 684 to guide hooks 685, into the vertical thread grooves of the slide 711, through thread eyes 713 to stationary take-up member 77, to movable take-up member 71, thread channel 298 in the wall of the work-arm, over rounded edge 53^a at the end of said channel, and through the thread eyes of plate 27 to the 70 loopers. 75

The action upon the looper-threads is diagrammatically illustrated in Fig. 10, wherein the first view is an approximation upon an abnormal scale of the elliptical path traveled by the point of each looper. The second view of Fig. 10 indicates that portion of the looper movement during which the take-up pulls back slack thread. The third view indicates that portion of the looper movement during which the take-up 85 gives up slack thread, and the fourth view that portion of the looper movement during which there is a pull off of thread through the tension plates.

Contrasted with looper-thread take-up means such as shown in the aforesaid Merritt patent, the take-up means of this invention present the following advantages:—(a) Moving the take-up nearer the loopers, results in locating between the take-up and 95 tension, thread-angles or turns which were before located between the take-up and loopers. Hence, less strength of pull is required of take-up in pulling thread back from the loopers; also less pressure on the tension plates against the thread is required to resist thread being pulled through the tensions rather than back from the loopers. (b) The substitution of the new take-up means for the old straightens the path of the thread, 105 particularly eliminating one sharp turn (that at thread-guiding hooks 686 of said Merritt patent) and its friction. (c) Because of the lessening of the strength of pull required of take-up, due to the lessening of the friction of turns and of tension (or either of same), weaker thread can be used. (d) The possibility of using lighter tension without danger of losing control of the thread (that is, of pulling thread through 110 the tension rather than from the loopers), gives better control of the setting of the stitches; that is, control of the amount of looper thread allowed to go into the stitches on the underside of the fabric, which to a certain extent determines the length of needle-thread loop which interlocks with the looper-thread. (e) Not only is the thread path straightened and less grip by tensions required, but the take-up is positioned at an intermediate point between tension devices and loopers, with turns or friction points distributed on both sides of the take-up. In 115 120 125

other words, there is an approximation of or tendency to balancing, or a more equal balancing, of the friction points on opposite sides of the take-up, on one side between the 5 take-up and loopers, and on the other side between the take-up and tension devices. Variations in the stitch formation are thus much more sensitive to adjustments of the tension devices.

10 What is claimed is:—

1. In a sewing machine, the combination with an approximately horizontal free-ended work-supporting part of a work-arm, of a looper-lever mounted on said part of the 15 work-arm upon an upright axis and movable longitudinally and also laterally thereon in an approximately horizontal plane, thread-carrying loopers on said lever at one side of its fulcrum, looper-thread take-up 20 means associated with said lever at the other side of its fulcrum and comprising a member attached to and movable with the lever, and a stationary member secured to the work-arm, the looper-threads extending 25 from said take-up members in the direction of the lever to the loopers.

2. In a sewing machine, the combination with a work-arm having an approximately horizontal hollow free-ended work-supporting part, stitch-forming parts operating at said free end of the work-supporting part of the work-arm and including thread-carrying loopers, an approximately horizontally disposed looper-lever carrying the loopers at 30 one end thereof movable longitudinally and also fulcrumed to turn laterally on an upright axis intermediate its ends, driving means imparting longitudinal and lateral movements to said lever at its other end, and 35 looper-thread take-up means comprising a movable member attached to and movable with the lever at its driven end and a coöperating stationary member attached to the work-arm.

45 3. In a sewing machine, the combination of a looper-lever mounted to move longitudinally and laterally in an approximately horizontal plane, a looper or loopers on said lever at one end thereof, driving means imparting movement to the other end of said 50 lever in a continuous curved path in an approximately horizontal plane, and looper-thread take-up means including a movable member attached to and actuated by the 55 lever and a coöperating stationary member.

4. In a sewing machine, the combination of a work-arm having an approximately horizontal free-ended hollow work-supporting part, a throat-plate thereon, stitch-form-

ing parts including one or more loopers operating within said free end of the work-arm, a looper-lever within said hollow work-supporting part of the arm and carrying said looper or loopers, means actuating said lever to impart movement to the looper or 60 loopers in an elliptical path in an approximately horizontal plane, and looper-thread take-up means including a movable member attached to the lever, and a stationary member, said members coöperatively acting upon 65 the looper-thread to take care of slack therein.

5. In a sewing machine, the combination of a work-arm having an approximately horizontal free-ended hollow work-supporting part, a throat-plate thereon, stitch-forming parts including one or more loopers operating within said free end of the work-arm, a looper-lever carrying said looper or 70 loopers at one end and movable longitudinally and laterally within said arm on an upright fulcrum, means actuating said lever at its other end to impart longitudinal and lateral movement thereto causing the looper or loopers to move in an elliptical path in a 75 plane approximately parallel to the throat-plate, and looper-thread take-up means including a movable member attached to the looper-lever between its fulcrum and driven end and a stationary member, said members 80 coöperatively acting upon the looper-thread to take care of slack therein.

6. In a sewing machine, the combination with a thread-carrying needle and driving connections therefor, of a looper-lever and 95 driving connections therefor, a thread-carrying looper on said lever acting in its movement into the needle-thread loops to slacken the looper-thread, and looper-thread take-up means associated with said looper-lever 100 and actuated thereby to take up the aforesaid slack of the looper-thread.

7. In a sewing machine, the combination with a thread-carrying needle and driving connections therefor, of a looper-lever and 105 driving connections therefor, a thread-carrying looper on said lever acting by its movement into the needle-thread loops to slacken the looper-thread, and looper-thread take-up means including a movable member 110 attached to the looper-lever and a stationary member said members coöperatively acting upon the looper-thread to take up the aforesaid slack therein.

In testimony whereof I have signed this 115 specification.

GARRET B. OSTERHOUT.
